W. KOCK.
Permutation Locks.

No. 146,191.

Patented Jan. 6, 1874.

UNITED STATES PATENT OFFICE.

WILHELM KOCK, OF CINCINNATI, OHIO.

IMPROVEMENT IN PERMUTATION-LOCKS.

Specification forming part of Letters Patent No. 146,191, dated January 6, 1874; application filed October 18, 1873.

To all whom it may concern:

Be it known that I, WILHELM KOCK, of Cincinnati, in the county of Hamilton and State of Ohio, have invented a new and Improved Permutation-Lock, of which the following is a specification:

In the accompanying drawing, Figure 1 represents a front elevation of my improved permutation-lock, showing dial-plate and knob; Fig. 2, a vertical transverse section of the same. Figs. 3 and 4 are sectional rear elevations, showing the lock, respectively, in closed and open position; Figs. 5 and 6, detail front and side elevations of the tumblers, showing their setting mechanism. Fig. 7 is a detail sectional view of the pendulum-lever, showing manner of releasing the pivoted fence-lever; and Fig. 8 is a side view of the cylindrical bolt with recessed face-disk, into which the safe-bolt passes for opening the door.

Similar letters of reference indicate corresponding parts.

The invention will first be fully described, and then pointed out in the claims.

In the drawing, A represents the case of the permutation-lock, which is applied in the usual manner to the safe, vault, or other door. It is provided with a knob, B, and face dial-plate, which is marked with letters, numerals, or other signs, and turns on a washer-plate, B', with the index-marks for operating the tumblers which are set thereon. The spindle C of the dial-plate B passes through the outer face-plate of the safe-door, and turns freely in a tube, a, to which the flanged bushings b are keyed. The tumblers D turn freely on bushings b, the flanged part thereof keeping them at the required distance from each other. Each tumbler D is made of three concentric rings—an inner ring, d, which turns in a wider outer one, d¹, and is retained therein by the third top ring, d². The top ring d² is applied to the outer ring d¹ by two screws, e, which are placed near together at one side thereof, so that the other side acts like a band-spring on the lower rings. A pin, e¹, is applied to the inner side of top spring-ring d², so as to fit into the perforations e² of inner ring d, which are arranged along the circumference of the same. The inner ring d is furthermore supplied with a projecting pin or tooth, f, which slides in a

circular groove of the adjoining tumbler, formed by top ring d² and inner ring d, and acts on a pivoted tongue, f'. The tongue f' is applied, by means of a screw-pivot, into a recess of the shoulder of the inner ring d on that side opposite to pin f, and only allowed to swing far enough to either side that the pin f of the next tumbler D assumes a position radial and central to the pivoted part of tongue f', whether acting thereon from the right or left side. The pins f of tumblers D are in the same axis when all are brought to act on the tongues f' of the adjoining tumblers. Each tumbler is provided at its circumference with a dovetailed recess, h, between screws e, and is also provided, diametrically opposite to it, in the outer ring d¹, with a recess, h', into which the wedge-shaped tooth E¹ of lever E enters, so as to lift the top ring d² and disconnect the perforated inner ring d, for adjustment to the letters selected for the combination. Lever E has as many teeth E¹ as there are tumblers in the lock, and is pivoted to a standard, F, cast to case A, and operated by a pivoted knob, E², the stem of which slides in a slot, i, of the case A, and is firmly secured in said slot i by a projecting lug, i', when not in use. The revolving driving-wheel G is rigidly screwed to the end of spindle C by top washer-plate l and screw l². Wheel G is also provided with a pin, f, which acts in similar manner on the first tumbler D as the other tumblers on each other. A circumferential groove, m, in wheel G serves to admit a small anchor-shaped pendulum, n, pivoted to the end of lever H in such a manner that it does not come in contact with the inner circumference of groove m. Two cross-pins, n', Fig. 7, (of which one is a rear extension of pin f,) serve to engage, at the proper time, the end of pendulum n, lift it, and thereby lever H, so that its check-lug o releases the fence-lever I. Lever H is also pivoted to standard F opposite to lever E. Fence-lever I is pivoted to the extension-arm of bolt-lever L, whose central ring-shaped part turns on a shoulder, p, of wheel G, while its opposite arm engages, by a slotted downward extension, L', the guide-pin q of bolt M. The lever I is of curved shape, and carries, at right angles to it, the tapering fence I', which enters the dovetailed recesses h of tumblers D. Its fore part slides

easily on check-lug o , while its hook-shaped projection r passes along the circumference of wheel G , and enters the recess r' of the same, when fence I' enters the tumbler-recesses h , and check-lug o releases its end. The wheel G , and with it bolt-lever L , is then carried forward and bolt M turned. Bolt M turns in standard F , and with its disk-shaped face M' in a circular opening of the side plate of case A . A recess, s , for the main bolt of the safe-door, extends from the face-disk into the solid part thereof, and allows the entering of the door-bolt when the lock is in open position. The exact position and motion of the face-recesses s are defined by the slotted extension L' , which slides on the upper surface of standard F .

For opening the lock, the dial-knob is turned in one direction till the pin of driving-wheel engages the tongue of the first tumbler, the pin of the first tumbler the tongue of the second, and so on until all the tumblers are in motion. The dial-plate is then set with the first letter selected to the index-mark, carried thence in opposite direction to the second letter, and so on alternately in opposite directions till the tumblers are in position for admitting the fence of the fence-lever. The driving-wheel is then set so that the pendulum rests upon the cross-pins; then lifting, by a return motion of the knob, the pendulum-lever and releasing the fence-lever, which engages

the driving-wheel and rotates the bolt-lever and bolt, bringing the recess of the face-disk into position to receive the bolt of the safe-door.

The lock may be set to any combination of letters on the dial-plate by placing the tumblers into their position, as described, by using, instead of the index-mark, which is vertically above the dial-plate, the side mark, which brings the recesses of the tumblers under the spring-rings in position for the action of the wedge-lever, and allows the entering of the wedge-teeth and the changing of the tumblers to any desired combination of letters. The wedge-lever is then withdrawn and the lock opened on the index-mark.

Having thus described my invention, I claim as new and desire to secure by Letters Patent—

1. The combination of the revolving driving-wheel G with the pendulum-lever H n and fence-lever I , to release the same for acting on the bolt-lever at the required time, substantially in the manner described.

2. The driving-wheel G , having groove m , cross-pins n' , and recess r' , for throwing up the pendulum-lever and engaging the fence-lever, as described.

WILHELM KOCK.
